United States Patent Office

Des. 227,535
Patented July 3, 1973

227,535

PITCHER

Gary S. Grimes, Twin Lakes, Ohio, assignor to Questor Corporation, Toledo, Ohio

Filed Dec. 27, 1971, Ser. No. 212,867

Term of patent 14 years

Int. Cl. D7—01

U.S. Cl. D7—64

FIG. 1 is a top perspective view of a pitcher showing my new design;

FIG. 2 is a top plan view thereof;

FIG. 3 is a side elevational view thereof; and

FIG. 4 is a front elevational view thereof.

I claim:

The ornamental design for a pitcher, as shown.
